M. ZERILLI

TOILET ARTICLE

Filed March 1, 1924

UNITED STATES PATENT OFFICE.

MARIUS ZERILLI, OF GLENDALE, NEW YORK, ASSIGNOR TO LEW JOSEPH, OF NEW YORK, N. Y.

TOILET ARTICLE.

Application filed March 1, 1924. Serial No. 696,128.

To all whom it may concern:

Be it known that I, MARIUS ZERILLI, a citizen of the United States, residing at Glendale, county of Queens, and State of New York, have invented certain new and useful Improvements in Toilet Articles, of which the following is a specification.

This invention relates to articles for toilet use, such as hand mirrors, brushes and various other articles.

In articles of the character hereinafter stated, weight is one of the important features in order to give satisfaction to the user.

A desired thickness is another feature essential to a hand mirror to meet with general acceptance in the trade.

Heretofore, in order to produce a desired thickness, it has been found necessary to insert a filling of ground material, such as plaster, or whiting, which is inserted in a semi plastic condition within the frame of the glass. A thin backing has been placed over such material, but it has been found that the action of such filling on the material forming the backing produces unfavorable results, including a tendency of the outer backing to separate from the filling material.

In such prior constructions moreover, the outer backing on one side of a hand mirror has generally been embossed, and the glass of the mirror inserted therein.

A fillet, necessarily light in structure, has been used to hold the glass in place, which fillet has a tendency to separate from the adjacent margin of the backing, thereby not only loosening the hold on the glass, but also presenting an unsightly appearance.

This invention has for its main objects to provide an article for toilet use, such as a hand glass or brush, that is strong and durable in construction, adapted to be made at a minimum of cost, relative to its structure and advantages, of the desired weight and thickness, and attractive in appearance.

With the foregoing, and other objects in view, hereinafter stated, the invention consists of the novel construction, combination and arrangement of parts hereinafter more specifically stated, and illustrated in the accompanying drawings, wherein is shown a device embodying the structure of the inven-

tion in its preferred form, but it is to be understood that changes, variations and modifications may be resorted to without departing from the scope of the invention.

In describing the invention in detail, reference is had to the accompanying drawings, which form a part of this specification, and wherein like characters of reference indicate corresponding parts throughout the several views, and wherein:

Fig. 1 is a plan view, partly broken away, of a hand mirror embodying the invention.

Fig. 2 is a vertical section taken on the line 2—2 of Fig. 1.

Fig. 3 is a plan view of a brush embodying the invention, and

Fig. 4 is a vertical section taken on the line 4—4 of Fig. 3.

As illustrated in Fig. 1 of the drawing, the hand mirror is provided with a back plate having a body portion 1, and a handle portion 2. The back plate may be made of any suitable material, preferably celluloid, and of uniform thickness throughout. A front plate is provided with a handle portion 3, and an open body portion 4, overlapping at its inner edge a mirror 5.

The handle and body portions are preferably of uniform thickness throughout and the outer margins thereof correspond with the outer margin of the body and handle portions of the back plate, and are preferably in substantially vertical alignment therewith. An intermediate open marginal frame 6 is arranged between the body portion and handle of the front and back plates and bears against the outer margin of the body and handle portions of said plates.

The intermediate open frame 6 is narrow in width, and preferably of approximately the same thickness as width, so as to space the body and handle of the front and back plates at the desired distance from each other.

Filling material, such as cardboard 7, in a single layer, or a plurality of layers is placed within said intermediate open frame and against the back of the mirror, and a filler of lead or cardboard corresponding in thickness and in line therewith is inserted within the open intermediate frame between the handle portion 3 of the frame section 100 and the lead filling 7.

Weight is added to the article by means of one or more layers of sheet lead 8, placed within said open intermediate frame against the cardboard and preferably between the cardboard and back of the mirror.

In assembling the parts the open intermediate frame 6 is placed upon the body and handle of the back plate, and the layers of cardboard and lead placed within said frame. The mirror is then placed upon the lead or cardboard, and the front plate placed over the mirror with the inner margin of the opening of the front plate overlapping the outer edge of the mirror.

15 When the parts are so arranged the back plate is cemented to the back of the open intermediate frame, and the front plate is cemented to the front of said open frame and the inner margin of the opening of the front plate is cemented to the outer margin of the mirror.

20 By means of such construction and arrangement a hand mirror is provided that is strong and simple in construction, pleasing 25 in appearance, and of any desired weight and thickness.

25 None of the parts require embossing to give the desired hold on the mirror, or any filler to hold the mirror in place.

30 The material forming the front and back plates are not subjected to any injurious heat in securing the parts together, and the parts are not liable to become separated when in use.

35 Figs. 3 and 4 show the invention applied to a hand brush.

In such construction a back plate 9, and an intermediate open frame 10 are provided similar in general construction to the back plate and intermediate open frame shown in Figures 1 and 2. Cardboard 11 and one or more sheets of lead 12 may be inserted within the open intermediate frame 10.

40 The back of block 13 of a brush having bristles 14 inserted therein is placed within the open frame 10 and is held in position by means of the marginal edge 15 of the opening of the front plate overlapping the outer margin of the brush block.

45 A filling 16 of lead or cardboard corresponding in thickness with the brush back may be inserted within the handle portion of the intermediate frame 10 and the parts cemented together in the same manner as in the case of the hand mirror.

What I claim as new and desire to secure by Letters Patent, is:

1. A toilet article having a back plate formed with a body section and a handle section, a front plate having an open body section and a handle section, an intermediate open frame extending around and between the outer margins of said back plate and front plate with its outer wall in line with the edges of said plates, a sheet of weight 60 ing material and a sheet of filling material within the body and handle portions of said intermediate frame of smaller area than that of said back plate, a toilet accessory within said open intermediate frame with 65 its outer margin beneath the inner margin of the opening of said front plate and a sheet of filling material within the handle portion of said open intermediate frame in line with said toilet accessory and of sub- 70 stantially equal thickness therewith.

2. A toilet article having a back plate formed with a body section and a handle section, a front plate having an open body section and a handle section, an intermediate open frame extending around and between the outer margins of said back plate and front plate, sheet filling material within the body and handle portions of the intermediate frame of smaller area than that of 80 said back plate, a toilet accessory within said open intermediate frame with its outer margin beneath the inner margin of the opening of said front plate and sheet filling material within the handle portion of said 85 open intermediate frame in line with said toilet accessory and of substantially equal thickness therewith.

3. A toilet article having a back plate formed with a body section and a handle section, a front plate having an open body section and a handle section, an intermediate open frame extending around and between the outer margins of said back plate and front plate, a toilet accessory within 90 said open intermediate frame with its outer margin beneath the inner margin of the opening of said front plate, and filling material within said open intermediate frame between said back plate and toilet accessory, 10 and between the handle sections of said back plate and front plate.

In testimony whereof I have affixed my signature.

MARIUS ZERILLI.
